KEY HOLDER FRAME

Frank E. Johnson, Abington, Mass., assignor to
 United-Carr Fastener Corporation, Cambridge,
 Mass., a corporation of Massachusetts

Application September 17, 1949, Serial No. 116,245

5 Claims. (Cl. 70—456)

1

This invention relates generally to key retaining devices, and has particular reference to a key holder frame adapted to receive key hooks of the type having an enlarged head disposed on the end of a neck portion.

The object of the invention is to provide a key holder frame in which spring arms spaced to receive a key hook therebetween are provided with free ends for snapping engagement with spaced tongue members.

A further object of the invention is to provide a key holder frame in which a series of spring arm pairs which are adapted to receive a key hook therebetween are provided with means for engaging spaced tongue members so that a continuous slot is formed between the arms and the tongues to receive a key hook.

A further object of the invention is to provide a key holder frame having a pair of spring arms extending upwardly and outwardly in spaced relation to a base in which the arms are adapted to be sprung inwardly for engagement with spaced tongues to form slots to receive a key hook therein.

A further object of the invention is to provide a key frame having the features as described above which is formed of a single piece of sheet metal and adapted for manufacture from a continuous strip of material on an automatic machine.

Other objects of the invention will, in part, be obvious, and will, in part, appear hereinafter. For a fuller understanding of the nature and objects of the invention, reference should be had to the following detailed description, taken in conjunction with the accompanying drawing, in which:

Fig. 1 is a perspective view of a key holder frame embodying the features of the invention;

Fig. 2 is an enlarged plan view of a portion of the key holder frame of Fig. 1;

Fig. 3 is a view in section taken on line 3—3 of Fig. 2;

Fig. 4 is a top plan view of the key holder of Fig. 2;

Fig. 5 is a view in section of the key frame taken on line 5—5 of Fig. 2 and a key hook in position for removal from the frame; and

Fig. 6 is a view in section taken on line 6—6 of Fig. 2.

Referring to the drawing, there is illustrated a key holder frame 10, which is adapted for attachment to a supporting member 12, such as a key case or the like, to receive and engage key hooks 14.

The key frame 10 comprises a base 16, which may be provided with openings 18 to receive rivets 20 for attaching the frame to the supporting

2

member, a series of tongues 22 disposed on the upper portion of the base, and a series of spring arms 24 disposed on the lower portion of the base having free end portions 26 extending upwardly in spaced relation thereto.

The tongues 22 are spaced apart to form a series of upper slots 28, and in the preferred embodiment are integral with the upper edge of the base, and are curled outwardly and then downwardly to form a support portion 30 which is spaced apart from the base to engage the free end portions 26 of the spring arms and retain them in an inwardly flexed position as will be hereinafter described.

15 The spring arms 24 are arranged on the base in cooperating pairs 32, with the arms of each pair spaced apart to form a series of lower slots 34, and the spring arm pairs are so spaced on the base that each lower slot 34 is in alignment with an upper slot 28. Each arm 24 is provided with a tongue engaging member 36 which extends inwardly from the free end of the arm toward the plane of the base. The member 36 is provided with a tongue engaging edge 38 having a camming portion 40 leading to a shoulder portion 42 which is adapted to snap behind the edge of the support portion 30 of a tongue 22. The tongue engaging edge 38 is disposed on the opposite outer edges of the tongue engaging members of each spring arm pair, to enable the edges 38 of a pair of arms to snap into latching engagement with adjacent edges of adjacent tongues so that the lower slot 34 and the upper slot 28 form a continuous slot to retain a key hook therein. The inner edges of the tongue engaging portions on each pair of arms are provided with outwardly rounded portions 43, which cooperate to form an opening 44 which is wider than the slots 28 and 34, to allow the head of a key hook to pass therethrough.

40 The key hooks 14 for use with the key holder frame of the invention are well known in the art, and comprise generally a key retaining loop 46 and a pair of legs 48 which are held together by the spring action of the loop and adapted to be sprung apart to allow a key to be assembled on the loop. To provide means for engagement with the key holder frame, the legs 48 are shaped and arranged to provide an enlarged head 50 disposed on the end of a neck portion 52.

45 Referring to Fig. 5, there is illustrated the method of assembling a key hook on the key frame. The free end portions 26 of the spring arms, when not engaged with a tongue, extend upwardly and outwardly at an angle to the base, so that the opening 44 formed between the tongue engaging members of the arm pairs is disposed outwardly from the tongues (see Fig. 6) and is

thereby accessible to allow the head of a key hook to be passed therethrough. As the head enters the opening, the neck 52 of the hook enters the lower slot 34, so that the head of the hook is retained behind the adjacent edges of the spring arms. The free end portions 26 are then pushed inwardly to snap into latching engagement with adjacent edges of the tongues, whereby the lower slot 34 and the upper slot 28 form a continuous slot to retain the key hook therein. The portion of the tongue engaging members forming the opening 44 is now disposed beneath the tongues 22 and although the head 50 of the key hook can move freely up and down in the slot through the opening, it is prevented from becoming disengaged from the frame when the head passes upwardly through the opening 44, since the head is retained by the edges of the tongues 22.

To remove a key hook from the frame, the spring arms between which the hook is retained are forced toward each other until the shoulder 40 of each arm passes the edge of the support portion of the tongue. The free ends of the arms then spring outwardly into the position illustrated in Fig. 5 and the head of the key hook may then be passed through the opening 44.

The key holder frame of the invention is economical to construct, since it is formed of a single piece of metal, which allows it to be formed on an automatic machine from a continuous strip of sheet metal. The construction of the arms insures that the key hook is positively locked in the slot, thereby eliminating the possibility of accidental loss of a key.

Since certain obvious changes may be made in the device without departing from the scope of the invention, it is intended that all matter contained herein be interpreted in an illustrative rather than in a limiting sense.

I claim:

1. A key holder frame to receive and engage key hooks, said frame comprising a base, a series of outwardly extending tongues disposed on the base in spaced relation to one another to form an upper series of slots, and a series of spring arms disposed on the base below the tongues in spaced relation to one another to form a lower series of slots, said arms extending upwardly in spaced relation to the base and having latching means thereon for latching engagement with the tongues so that the upper slots and the lower slots form a series of continuous slots for retaining key hooks therein.

2. A key holder frame to receive and engage key hooks, said frame comprising a base, a pair of outwardly extending tongues disposed on the base in spaced relation to one another to form a slot, and a pair of spring arms disposed on said base in spaced relation to said tongues, the arms of said pair being spaced apart to form a slot therebetween, the arms of said pair being so disposed with respect to said tongues as to align the slot of said pair with the slot formed by said tongues, and the arms of said pair extending upwardly in spaced relation to the base and having latching means thereon for latching engagement with the adjacent tongues so that the slot between said pair of arms and said corresponding slot form a continuous slot for receiving a key hook therein.

3. A key holder frame to receive and engage key hooks, said frame comprising a base, a series of tongues disposed on the base in spaced relation to one another to form a first series of slots, and pairs of spring arms disposed on the base in spaced relation to one another and to said series

of tongues and extending upwardly in spaced relation to the base, the arms of each of said pairs being spaced apart to form a slot therebetween, the slots formed by said pairs forming a second series of slots, and the arms of each pair having inwardly extending portions shaped and arranged to snap into latching engagement with adjacent tongues so that corresponding slots of said first and second series of slots form a series of continuous slots for retaining key hooks therein.

4. A key holder frame to receive key hooks of the type having an enlarged hook disposed on the end of a neck portion, said frame comprising a base, a series of tongues disposed on the base in spaced relation to form a series of slots, and pairs of spring arms, each pair of spring arms being disposed on the base in spaced relation to a corresponding slot of said series of slots, the arms of each pair being spaced apart to form a slot in alignment with the corresponding slot of said series of slots, the arms of each pair having inwardly extending tongue-engaging portions having a camming portion and a shoulder portion disposed thereon to enable the spring arm pairs to snap into engagement with the adjacent edges of adjacent tongues so that the slots of said pairs of arms and the corresponding slots of said series form continuous slots to retain key hooks therein.

5. A key holder frame to receive key hooks of the type having an enlarged head disposed on the end of a neck portion, said frame comprising a base, a series of outwardly extending tongues disposed on the base in spaced relation to form a first series of slots, and pairs of spring arms, each pair of spring arms being disposed on the base in spaced relation to a corresponding slot of said first series of slots, each arm of each pair being disposed in spaced relation to the other to form a slot in alignment with the corresponding slot of said first series of slots, the slots formed by said pairs of spring arms forming a second series of slots, the arms of each pair having free end portions extending upwardly and outwardly in spaced relation to the base, the free end portions of each pair of arms having inwardly extending tongue-engaging means adapted to snap into latching engagement with adjacent tongues when the free ends of the arms are pushed inwardly whereby the slots of said second series and the corresponding slots of said first series form a series of continuous slots to receive key hooks so that the enlarged head of the key hook is retained behind adjacent edges of the pairs of arms, said inwardly extending tongue-engaging means being shaped and arranged to provide an opening therebetween to allow the head of a key hook to pass therebetween when the arms are disengaged from the tongues and to pass under the tongues when the arms are engaged therewith, whereby the adjacent tongues cover said opening to retain a key hook in the slot.
